CLAIM

The ornamental design for a fastener, as shown and described.

DESCRIPTION

FIG. 1 is a front perspective view of a fastener showing my new design;

FIG. 2 is a front elevation view thereof, the rear elevation view being a mirror image thereof, therefore not shown;

FIG. 3 is a right side elevation view thereof;

FIG. 4 is a left side elevation view thereof;

FIG. 5 is a top plan view thereof; and,

FIG. 6 is a bottom elevation view thereof.
